VEHICULAR TRUCK FOR CARRYING SOFAS OR THE LIKE

Eddie R. Davis, Midland, Tex.

Application July 17, 1953, Serial No. 368,604

4 Claims. (Cl. 280—47.24)

This invention relates to a sofa truck, and more particularly to a hand truck having a flat base member pivotally mounted on a wheeled standard.

An object of the present invention is to provide a truck whereby one man can easily transport a sofa or the like.

Another object of the present invention is to provide a truck having an article supporting base member pivotally secured to a wheel carrying standard whereby the article can be easily loaded on or unloaded from the base member.

A further object of the invention is to provide a truck for carrying sofas or the like wherein the article carrying base member is pivotally secured to a wheel carrying standard to enable one man to easily maneuver the sofa or the like through a narrow opening.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a top view of a preferred form of the present invention;

Figure 2 is a side elevational view of a preferred form of the present invention, showing a sofa mounted thereon;

Figure 3 is a front end elevational view of the preferred form of the present invention, showing a sofa mounted thereon, with the dotted lines showing the sofa in various tilted positions; and

Figure 4 is an enlarged sectional view taken substantially along the section line 4—4 of Figure 1.

Referring now more specifically to the accompanying drawings, it will be seen that the improved sofa truck forming the subject of this invention includes, as shown in Figure 2, a base member 10, having a sofa 12 mounted thereon, pivotally secured to a standard 14. The base member 10, in the preferred form of the present invention, is formed of a pair of parallel longitudinally extending frame members 16 fixedly secured in spaced relation by a plurality of transverse members 18. One of the members 18 is secured to the adjacent ends of members 16 and the other members 18 are secured along the members 16 at spaced intervals. The other ends of the members 16 are provided with a curved portion 20 forming handles for the manipulation of the truck. The transverse members 18 at opposite ends of the members 16 are provided with straps 22 for securing an article on the base member 10. The straps 22 may be of canvas, leather, or any other suitable material, and may be provided with buckles or any other suitable slack take-up means for fixedly securing a sofa on the truck.

The standard 14 comprises an upright member 24 having a shaft 26 mounted thereto adjacent its lower end. Suitable brace means 28 are provided between the upright 24 and the shaft 26 for maintaining the shaft in fixed relation in respect to the upright member. A pair

2

of wheels 30 are rotatably mounted on opposite ends of the shaft 26.

A tubular member 32 is fixedly secured in perpendicular relationship to the upright 24 at the top thereof, 5 which tubular member extends in a direction transverse to the longitudinal axis of the shaft 26. Suitable brace means 34 are provided between the upright 24 and the tubular member 32 for maintaining the tubular member in fixed relationship with respect to the upright 24. The 10 transverse members 18 at the end opposite the handle portion of members 16 are each provided with a downwardly extending ear 36. The length of the tubular member 32 is such that it will fit between the ears 36. Each of the ears 36 is provided with an aperture 38 which 15 is aligned with the opening through the tubular member 32. A shaft 40 extends through the apertures 38 and through the opening in the tubular member 32. There is thus provided a pivotal mounting between the base member 10 and the standard 14.

In operation, the sofa is strapped to the top of the base member 10 and is easily transported from one place to another by means of one man lifting the handles 20 and pushing against the device. When it is desired to move the sofa between obstructions the operator simply tilts the sofa as shown in Figure 3 in order to clear the obstruction.

From the foregoing, the construction and operation of the device will be readily understood and further explanation is believed to be unnecessary. However, since 20 numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A sofa truck comprising a standard, a pair of wheels mounted for rotation on the lower end of said standard, and a base member pivotally mounted on said standard 30 at the upper end thereof, said base member pivoting about an axis transverse to the axis of rotation of the wheels, said standard comprising an upright member, a shaft mounted on the lower end of said upright member and perpendicular thereto, said wheels being mounted on the opposite ends of said shaft, a tubular member fixedly secured to the upper end of said upright in a direction transverse to said shaft, a pair of downwardly extending ears secured to the bottom of the base member adjacent one end thereof, each of said ears having an aperture therein, the apertures in the ears being axially aligned, said ears being spaced apart a distance greater than the length of said tubular member, whereby the tubular member will be received between the ears and a rod extending through the apertures in said ears and through the tubular member 45 whereby the base member is pivotally mounted on the standard.

2. The combination of claim 1 wherein the base member is provided with a pair of handles at the end opposite the connection to the standard and said base being provided with means for securing an article in fixed position on the top thereof.

3. A sofa truck comprising a standard, a pair of wheels mounted for rotation on a transverse shaft on a lower end of the standard, a base member pivotally mounted on the standard at an upper end thereof, said base member pivoting about an axis transverse to the shaft upon which the wheels are mounted, said standard including a longitudinal pivot shaft secured on an upper portion thereof and extending on opposite sides of and transverse to the shaft of the wheels, said base being provided with a pair of downwardly extending ears secured adj-

cent one end thereof, said ears being provided with axially aligned apertures receiving the opposite ends of said pivot shaft.

4. The combination of claim 3 wherein said standard includes an elongated tubular member at the upper end thereof, said pivot shaft being mounted in said tubular member.
